Patented July 21, 1914.

UNITED STATES PATENT OFFICE.

JOHN D. FIELDS, OF BUTTE, MONTANA.

ELECTROLYTIC APPARATUS.

1,104,646.

Specification of Letters Patent. Patented July 21, 1914.

Application filed March 11, 1913. Serial No. 753,523.

To all whom it may concern:

Be it known that I, JOHN D. FIELDS, a citizen of the United States, and a resident of Butte, in the county of Silverbow and State of Montana, have made certain new and useful Improvements in Electrolytic Apparatuses, of which the following is a specification.

My invention relates to improvements in electrolytic apparatuses, and it consists in the combinations, constructions, and arrangements herein described and claimed.

The primary object of my invention is to provide a novel electrolytic apparatus for the treatment of ores, especially copper ores in which the metal is deposited from a solution.

A further object of my invention is to provide an apparatus in which the cost of the production of metal is greatly reduced.

A further object of my invention is to provide an apparatus, the use of which results in a large economy of floor space, this being a very important item in a large reduction plant.

Other objects and advantages will appear in the following specification, and the novel features of the device will be particularly pointed out in the appended claims.

My invention is illustrated in the accompanying drawings forming part of this application in which—

Figure 1 is a plan view of a portion of the device, Fig. 2 is a vertical section through a portion of the device along the line 2—2 of Fig. 1, looking in the direction of the arrow, Fig. 3 is a diagrammatic plan view showing the general distribution of the electrolytic cells, and Fig. 4 is a section on the line 4—4 of Fig. 1.

In a good many of the plants in which copper is recovered by the electrolytic method the cells are made of wood, each wall of the cell and its bracing constituting a thickness of perhaps six inches. The cell is generally lined with a conducting metal such as antimonial lead. A series of conducting bars extends across the top of the cell from side to side, the alternate bars being connected at one end to a common bus bar and being insulated from the bus bar on the opposite side. The anodes are suspended from one series of cross bars and the cathodes from the other. It will be apparent that in this construction there must be a good many connecting joints thereby tend-

ing to increase the resistance. In order to prevent short circuiting there must be sufficient clearance between the edges of the plates and the side walls of the tank, thus a space is lost which otherwise might be utilized. I also reduce the floor space by eliminating the outer wooden frame and the braces therefor as will be explained later.

In carrying out my invention I provide a series of tanks such as those shown at A, B, C, D, E and F in Fig. 3. These tanks are made of some metal, preferably antimonial lead and consist of an outer casing 1 having a series of vertically extending ribs 2. These ribs terminate short of the end of the tank at an integral baffle plate 3 which extends downwardly from the top of the tank and terminates short of the bottom so as to leave a space or passage 4 for the liquid as hereinafter described. The ribs 2 serve a double purpose. In the first place they constitute anodes which are an integral part of the tank itself. This tends to greatly reduce the resistance over that from the tank in which the anodes are suspended from conducting bars. In the second place these ribs constitute strengthening members and they are so proportioned that there is no need of the exterior wooden casing which is generally used. Thus a tank constructed according to my invention takes up considerably less room.

At each end of the tank are supports such as the posts 5 upon the top of which is a cross member 6 (see Fig. 2) bearing an insulator 7 which is preferably of glass or other insulating material. A series of suspension bars 8 is provided for supporting the cathode plates 9 which are secured to the suspension bars by means of the lugs 9^x. The suspension bars 8 rest upon the top of one of the insulating plates 7 at one end of the tank and at the other end upon a bus bar 10 which is disposed on an insulating plate 11 carried by a suitable support such as the block or bracket 12.

The tanks A, B, C, D, E and F are arranged one slightly below the other, as shown in Fig. 2. An overflow trough 13 is provided at the end of each tank for permitting a flow of the fluid from one tank to the other. As will be seen in Fig. 2, the suspending bars 8^x of tank B are disposed below the end of the trough 13, and in order to prevent the fluid from coming in contact with the suspending bars 8^x I provide down

spouts 14 which conduct the fluid past the bars so that there is no danger of the latter being eaten away by the fluid falling upon it.

The tank A is connected with one of the 5 leads 15. A bus bar 10 is connected to the end of the adjacent tank by means of a suitable conductor 16. The tank B is similarly connected to the tank C. The bus bar 10 of the tank C is connected with the tank D 10 and the cathode supports of the latter tank are prolonged to rest on a conducting bus bar 10^x, as shown in Fig. 4. This bus bar is connected directly to the tank E by the conductor 16^x. The tank E is connected to the 15 tank F in a similar manner. Current is taken out at the conducting bus bar 10^x at the left of Fig. 3 by means of the lead 15^x. In the illustration the fluid is designed to enter from the left of both rows of tanks in 20 Fig. 3 and to flow toward the right.

From the foregoing description of the various parts of the device the operation thereof may be readily understood.

The current will enter by one of the leads 25 such as that shown at 15 and will pass through the walls of the tank A, thence from the anodes 2 to the cathodes 9, bus bar 10, conductor 16 to tank B, thence to tank C, and from its bus bar 10 to tank D, 30 through the anode to the cathode, and by bus bar 10^x and conductor 16^x to the tank E, on to tank F and out by means of the bus bar 10^x and the lead 15^x. It will be noted that instead of using the ordinary conduct- 35 ing bus bars which extend the entire length of the tank, a short conducting bus bar is used at the end of each tank. There is a vast saving in the copper conducting bars. In the ordinary tank these bus bars have to 40 be provided as carriers for both the anodes and cathodes, while in my device the tank itself is a carrier as well as a container. I do away with the long conducting bus bars on each side. I do away with the numerous 45 joints which tend to increase the electrical resistances. I utilize the space which is necessary in the ordinary construction for a clearance at the ends of the plates when they are placed transversely of the cell, thus pro- 50 viding a greater surface and hence cutting down the internal resistance of the cell, thereby saving in current. The doing away with the wooden frame, which, as stated before, is approximately six inches wide on 55 the sides and ends of the tank economizes greatly in floor space, permitting greater concentration of the cells. All these advantages reduce the cost of treatment considerably.

60 In the ordinary cell there is a great difference in the conductivity of the anode and the cathode. Assuming the conductivity of copper to be 100, and the conductivity of antimonial lead to be approximately 8 it 65 will be seen that there is a great difference

between the conductivity of the anode and the cathode. In certain instances it is desirable to increase the conductivity of the anode to approximately that of the cathode, and in such a case I prefer to make the cell 70 of aluminum. This tends to effect economy 75

A series of cells set up as described is convenient to handle, moreover there is less danger of short circuiting. In the ordinary cell the wooden frame is apt to become wet with the acid, thereby increasing the tendency to short circuits. In my device the absence of the frame prevents any such action.

I claim:—

1. In an electrolytic apparatus, an elongated tank of conducting material, a series of metal strengthening ribs integral with said tank and extending longitudinally thereof, said metal ribs dividing the tank into separate cells and constituting anodes, a series of conducting bars suspended above said tank, a cathode carried by each of said conducting bars, said cathode being disposed between adjacent anodes, a common conducting bus bar at the end of the cell having electrical connection with said conducting bars, an electrolyte disposed in said cell, an over flow trough at one end of said cell, and a baffle plate extending across one end of said cell near said over flow trough, said baffle plate terminating short of the bottom of the cell to provide a passage for the electrolyte.

2. In an electrolytic apparatus, an elongated tank of conducting material, a series of metal strengthening ribs integral with said tank and extending longitudinally thereof, said metal ribs dividing the tank into separate cells and constituting anodes, a series of conducting bars suspended above said tank, a cathode carried by each of said conducting bars, said cathode being disposed between adjacent anodes, a common conducting bus bar at the end of the cell having electrical connection with said conducting bars, an electrolyte disposed in said cell, an over flow trough at one end of said cell, and a baffle plate extending across one end of said cell near said over flow trough, said baffle plate terminating short of the bottom of the cell to provide a passage for the electrolyte, said baffle plate being integral with said metal tank and said anodes.

3. In an electrolytic apparatus, the combination of a series of cells, each cell comprising a metal tank, a plurality of integral strengthening plates disposed within the tank and extending longitudinally thereof, said plates constituting anodes, a transverse baffle plate near one end of the tank, said baffle plate being integral with the tank and with said anodes, an over flow trough at the end of the tank near said baffle plate, a conducting bus bar disposed above said trough, a plurality of conducting ribs, one end of

each of said ribs being connected to said conducting bus bar and the other end being insulated, and cathode plates suspended from each of said conducting bars between 5 adjacent anodes, the cells of the series being progressively lower in elevation.

4. In an electrolytic apparatus, the combination of a series of cells, each cell comprising a metal tank, a plurality of integral strengthening plates disposed within the tank and extending longitudinally thereof, said plates constituting anodes, a transverse baffle plate near one end of the tank, said baffle plate being integral with the tank 10 and with said anodes, an over flow trough at the end of the tank near said baffle plate, a conducting bus bar disposed above said trough, a plurality of conducting ribs, one

end of each of said ribs being connected to said conducting bus bar and the other end 20 being insulated, cathode plates suspended from each of said conducting bars between adjacent anodes, the cells of the series being progressively lower in elevation, down spouts connected with the over flow trough 25 of one cell and extending downwardly past the conducting bars which suspend the cathodes of the adjacent cell, and an electrical connection between the conducting bus bar of one cell and the metal tank of the adjacent lower cell.

JOHN D. FIELDS.
